UNITED STATES PATENT OFFICE.

ARTHUR G. KENT AND GEORGE M. WEGMAN, OF ROCHESTER, NEW YORK.

OPERATING DEVICE FOR GONGS, &c.

SPECIFICATION forming part of Letters Patent No. 766,264, dated August 2, 1904.

Application filed April 23, 1903. Serial No. 154,021. (No model.)

To all whom it may concern:

Be it known that we, ARTHUR G. KENT and GEORGE M. WEGMAN, citizens of the United States, and residents of Rochester, in the county of Monroe and State of New York, have invented a new and Improved Operating Device for Gongs, Sanding Apparatus, &c., of which the following is a specification, reference being had to the accompanying drawings, which 5 show our invention as applied to the operation of a street-car gong, only such portions of the gong and accompanying mechanism and supports being shown as are necessary to illustrate our invention.

15 The object of our invention is to overcome many of the difficulties attendant upon the usual construction and method of support of the operating push-bolt or punch for car-gongs, sanding mechanisms, &c., some of which 20 we will enumerate. Heretofore the push-bolt or punch for such purposes has usually been formed with a head on its upper end of such a conformation that it would either catch upon objects, such as articles of clothing, and 25 tear them or be removed from its place by them. The usual push-bolt has frequently operated to trip up a person striking against it with the foot. These difficulties we have sought to overcome by the construction and arrangement shown in the accompanying drawings.

30 Our invention presupposes a lever or other equivalent device which when operated by our punch or push-bolt either strikes the gong or actuates the other desired mechanism, either directly or indirectly, according to circumstances.

The accompanying drawings illustrating our invention are as follows:

40 Figure 1 is a vertical section of the supporting mechanism to our operating push-bolt or punch, such punch or push-bolt being shown in elevation. Fig. 1 shows also in vertical longitudinal section the supporting-bracket 45 for a gong when actuated by our operating punch or push-bolt. Fig. 2 is a plan view of the floor-plate *g* of Fig. 1 and with the webs *i* of the push-bolt or punch projecting therethrough. Fig. 3 is a perspective view of the 50 push-bolt removed. Fig. 4 shows partially in vertical section and partially in elevation a

modified form of our push-bolt or punch and with the floor-plate *g* also shown in vertical section.

Similar letters refer to similar parts throughout the drawings.

Referring to the drawings, *a* is an iron base-plate secured to the under side of the floor *l* of the car and to which is secured in the usual manner the gong *b*. The striking-lever *e* is 60 pivoted in the usual way to projections *d*, carried by this plate *a*. The lower end of this lever *e* carries the striking knob or ball *c*. Projecting upward from the base-plate *a* and into a hole in the floor *l* of the car is seen the 65 sleeve *o*, bored out to fit and form a guide for the stem of the bolt or punch *f*, the lower end of which rests upon the upper end of the lever *e* in such a way that the downward motion of such push-bolt or punch *f* causes the lever 70 *e* to be so moved that the knob *c* strikes the gong *b* in the usual way. Around this sleeve *o* and through the plate *a* there is formed a series of holes *n*, which are arranged, as seen, within the opening through the floor *l* of the 75 car, so as to allow the dirt, which might otherwise accumulate in such opening, to fall therethrough.

Inclosing the sleeve *o* and with its lower end resting upon the plate *a* is seen the coiled 80 spring *s*, arranged to engage at its upper end the under surface of the head of the punch or push-bolt *f* or the under surface of the webs *i* formed thereon. The head of our push-bolt may be formed either as shown in Fig. 85 3, in two semicircular webs arranged at right angles, or nearly so, to each other and with their convex surfaces upward, or it may be hemispherically formed and preferably hollow, as shown in Fig. 4. When webs are 90 used, as shown in Figs. 1, 2, and 3, their outer ends are connected by means of a rim *h*, the upper surface of which engages the under side of the floor-plate *g*, through which there are cut, as indicated in Figs. 1 and 2, slots to 95 admit the webs *i* on the upper end of the push-bolt. The tension of the spring *s* is so adjusted as to hold the push-bolt in its normal position, but it need not be sufficient to materially oppose the effort put forth in the 100 operation of the push-bolt.

As the result of the construction and ar-

angement just described it will be seen that the downward motion of the push-bolt operates the gong in the usual way, that the push-bolt is guided in the sleeve *o*, and that it is held in place by the floor-plate *g*, that it may be removed only upon the removal of the floor-plate *g*, which may be screwed to the floor in the usual way and which, it should also be noted, is integral or in one piece. It will also be noted that the conformation or the head of the push-bolt or punch *f* is such that nothing can catch upon it, and any objects striking it, as the foot of a person in walking by it, will cause it to be forced downward instead of its operating as a stumbling block. The base-plate *a* may be secured to the under side of the floor *l* of the car in the usual way. When the modified form of our push-bolt shown in Fig. 4 is used, it is preferable that the spring *s* be so proportioned as to engage the projecting rim seen at the lower end of the head thereof, engaging the under side of the floor-plate *g*.

By forming the under side of the head *f* of our operating-bolt with surfaces extending upward and inward from the outer and lower periphery thereof it is possible to use our operating-bolt in a gong-frame in which the guiding-sleeve *o* extends upward to a point nearly on a level with the floor-plate *g*.

What we claim is—

1. A mechanism to be operated, a push-bolt having a head thereon for actuating such mechanism, a plate for holding such push-bolt in place, means independent of such plate and of the head on such push-bolt for supporting and guiding such push-bolt in a fixed pathway independent of any contact between such bolt or head thereon and such plate except at one end of the travel of such push-bolt, such push-bolt removable from such supporting and guiding mechanism on the removal of such plate and having an operating-head thereon extending through such plate and with the top thereof slanting downward and outward to points at all times beneath the surface of such plate.

2. A mechanism to be operated, a push-bolt having a head thereon for actuating such mechanism, a plate for holding such push-bolt in place, means independent of such plate and of the head on such push-bolt for supporting and guiding such push-bolt in a fixed pathway independent of any contact between such bolt or head thereon and such plate except at one end of the travel of such push-bolt, such push-bolt removable from such supporting and guiding mechanism on the removal of such plate and having an operating-head thereon extending through such plate and with the top thereof slanting downward and outward in all directions from practically the center thereof to a base-line at all times beneath the surface of such plate.

65 3. A mechanism to be operated, a push-bolt

having a head thereon for actuating such mechanism, a plate for holding such push-bolt in place, means independent of such plate and of the head on such push-bolt for supporting and guiding such push-bolt in a fixed pathway independent of any contact between such bolt or head thereon and such plate except at one end of the travel of such push-bolt, such push-bolt removable from such supporting and guiding mechanism on the removal of such plate and having an operating-head thereon extending through such plate and with the top thereof slanting downward and outward to points at all times beneath the surface of such plate, such operating-head concave on its under side and slanting upward and inward from near its outer and lower periphery to its juncture with the body of such bolt.

4. A mechanism to be operated, a push-bolt having a head thereon for actuating such mechanism, a plate for holding such push-bolt in place, means independent of such plate and of the head on such push-bolt for supporting and guiding such push-bolt in a fixed pathway independent of any contact between such bolt or head thereon and such plate except at one end of the travel of such push-bolt, such push-bolt removable from such supporting and guiding mechanism on the removal of such plate and having an operating-head thereon extending through such plate and with the top thereof slanting downward and outward in all directions from practically the center thereof to a base-line at all times beneath the surface of such plate, such operating-head concave on its under side and slanting upward and inward from near its outer and lower periphery to its juncture with the body of such bolt.

5. A gong-operating lever and a push-bolt having a head thereon for actuating such lever, a plate for holding such push-bolt in place, means independent of such plate and of the head on such push-bolt for supporting and guiding such push-bolt in a fixed pathway independent of any contact between such bolt or head thereon and such plate except at one end of the travel of such push-bolt, such push-bolt removable from such supporting and guiding mechanism on the removal of such plate and having an operating-head thereon extending through such plate and with the top thereof slanting downward and outward to points at all times beneath the surface of such plate.

6. A gong-operating lever and a push-bolt having a head thereon for actuating such lever, a plate for holding such push-bolt in place, means independent of such plate and of the head on such push-bolt for supporting and guiding such push-bolt in a fixed pathway independent of any contact between such bolt or head thereon and such plate except at one end of the travel of such push-bolt, such push-bolt removable from such supporting and guiding mechanism on the removal of such plate.

plate and having an operating-head thereon extending through such plate and with the top thereof slanting downward and outward in all directions from practically the center 5 thereof to a base-line at all times beneath the surface of such plate.

7. A gong-operating lever and a push-bolt having a head thereon for actuating such lever, a plate for holding such push-bolt in place, means independent of such plate and of the head on such push-bolt for supporting and guiding such push-bolt in a fixed pathway independent of any contact between such bolt or head thereon and such plate except at one 15 end of the travel of such push-bolt, such push-bolt removable from such supporting and guiding mechanism on the removal of such plate and having an operating-head thereon extending through such plate and with the 20 top thereof slanting downward and outward to points at all times beneath the surface of such plate, such operating-head concave on its under side and slanting upward and inward from near its outer and lower periphery to its 25 juncture with the body of such bolt.

8. A gong-operating lever and a push-bolt having a head thereon for actuating such lever, a plate for holding such push-bolt in place, means independent of such plate and of the head on such push-bolt for supporting and guiding such push-bolt in a fixed pathway independent of any contact between such bolt or head thereon and such plate except at one 30 end of the travel of such push-bolt, such push-bolt removable from such supporting and guiding mechanism on the removal of such plate and having an operating-head thereon extending through such plate and with the top thereof slanting downward and outward 35 to in all directions from practically the center thereof to a base-line at all times beneath the surface of such plate, such operating-head concave on its under side and slanting upward and inward from near its outer and lower periphery to its juncture with the body of such bolt.

9. A mechanism to be operated, a push-bolt having a head thereon for actuating such mechanism, for holding such push-bolt in place a flat plate substantially flush with the base or support therefor, means independent of such plate and of the head on such push-bolt for supporting and guiding such push-bolt, such push-bolt removable from such supporting and guiding mechanism on the removal of such plate and having an operating-head thereon extending through such plate and with the top thereof slanting downward and outward to points at all times beneath the surface of such plate.

60 10. A mechanism to be operated, a push-bolt having a head thereon for actuating such mechanism, for holding such push-bolt in place a flat plate substantially flush with the base or support therefor, means independent of such 65 plate and of the head on such push-bolt for

supporting and guiding such push-bolt, such push-bolt removable from such supporting and guiding mechanism on the removal of such plate and having an operating-head thereon extending through such plate and with the top thereof slanting downward and outward in all directions from practically the center thereof to a base-line at all times beneath the surface of such plate.

11. A mechanism to be operated, a push-bolt having a head thereon for actuating such mechanism, for holding such push-bolt in place a flat plate substantially flush with the base or support therefor, means independent of such plate and of the head on such push-bolt for supporting and guiding such push-bolt, such push-bolt removable from such supporting and guiding mechanism on the removal of such plate and having an operating-head thereon extending through such plate and with the top thereof slanting downward and outward to points at all times beneath the surface of such plate, such operating-head concave on its under side and slanting upward and inward from near its outer and lower periphery to its juncture with the body of such bolt.

12. A mechanism to be operated, a push-bolt having a head thereon for actuating such mechanism, for holding such push-bolt in place a flat plate substantially flush with the base or support therefor, means independent of such plate and of the head on such push-bolt for supporting and guiding such push-bolt, such push-bolt removable from such supporting and guiding mechanism on the removal of such plate and having an operating-head thereon extending through such plate and with the top thereof slanting downward and outward in all directions from practically the center thereof to a base-line at all times beneath the surface of such plate, such operating-head concave on its under side and slanting upward and inward from near its outer and lower periphery to its juncture with the body of such bolt.

13. A gong-operating lever and a push-bolt having a head thereon for actuating such lever, for holding such push-bolt in place a flat plate substantially flush with the base or support therefor, means independent of such plate and of the head on such push-bolt for supporting and guiding such push-bolt, such push-bolt removable from such supporting and guiding mechanism on the removal of such plate and having an operating-head thereon extending through such plate and with the top thereof slanting downward and outward to points at all times beneath the surface of such plate.

14. A gong-operating lever and a push-bolt having a head thereon for actuating such lever, for holding such push-bolt in place a flat plate substantially flush with the base or support therefor, means independent of such 125 130

plate and of the head on such push-bolt for supporting and guiding such push-bolt, such push-bolt removable from such supporting and guiding mechanism on the removal of 5 such plate and having an operating - head thereon extending through such plate and with the top thereof slanting downward and outward in all directions from practically the center thereof to a base-line at all times beneath the surface of such plate.

15. A gong-operating lever and a push-bolt having a head thereon for actuating such lever, for holding such push-bolt in place a flat plate substantially flush with the base or support therefor, means independent of such plate and of the head on such push-bolt for supporting and guiding such push-bolt, such push-bolt removable from such supporting and guiding mechanism on the removal of 15 such plate and having an operating - head thereon extending through such plate and with the top thereof slanting downward and outward in all directions from practically the center thereof to a base-line at all times beneath the surface of such plate, such operating - head 20 concave on its under side and slanting upward and inward from near its outer and lower

periphery to its juncture with the body of such bolt.

16. A gong-operating lever and a push-bolt having a head thereon for actuating such lever, for holding such push-bolt in place a flat plate substantially flush with the base or support therefor, means independent of such plate and of the head on such push-bolt for supporting and guiding such push-bolt, such 35 push-bolt removable from such supporting and guiding mechanism on the removal of such plate and having an operating - head thereon extending through such plate and with the top thereof slanting downward and 40 outward in all directions from practically the center thereof to a base-line at all times beneath the surface of such plate, such operating-head concave on its under side and slanting upward and inward from near its outer 45 and lower periphery to its juncture with the body of such bolt.
